FABRIC TAKE-UP FOR KNITTING MACHINES

Rodney C. Southworth, Providence, R. I., assignor
to Hemphill Company, Central Falls, R. I., a
corporation of Massachusetts

Application October 23, 1941, Serial No. 416,138

11 Claims. (Cl. 66—153)

This application involves an invention in fabric take-ups such as are used in knitting machines, especially in circular hosiery knitting machines.

In the figures of the drawings:

Fig. 1 is an elevation showing part of a knitting machine to which the invention has been applied;

Fig. 2 is a similar elevation but illustrating the side of the machine;

Fig. 3 is a section through the take-up showing parts thereof in operative relationship;

Fig. 4 is a section taken on line 4—4 of Fig. 3;

Fig. 5 is a section through the lower part of the needle cylinder and driving gears, the take-up being connected to one of the driving gears;

Fig. 6 is a plan view of the take-up with a fabric guiding plate in position;

Fig. 7 is a similar view with the said fabric guiding plate removed;

Fig. 8 is a section showing in detail one of the driving ratchets and ratchet wheels for a fabric engaging roller;

Fig. 9 is a detail showing a double pawl and ratchet wheel drive for the take-up rollers; and

Fig. 10 is a detail of the fabric engaging rollers, ratchet wheels for driving them and stop pawls.

In circular type hosiery machines such as the well-known Banner knitting machine, it is customary to use a fabric take-up in certain instances, one example of such use being that of drawing the fabric from the needles when knitting string work. This is especially desirable when knitting string work in which elastic top stockings are being made, the said machine then being fully automatic in its operation.

Sometimes such string work is knitted without the commonly employed breaking or separating courses between individual knitted articles, but rather drawing the fabric through and connecting the latter to be separated stockings by wrap threads extending from the last point in which such threads might be knitted in one article to the first point in which they are incorporated in the next. That is commonly practiced at this time and so long as a sufficient number of wrap threads are used so that they have the necessary strength for maintaining the connection, there is no need for knitting breaking or separating courses, it being well-known that these are costly from the point of view of material and furthermore, since they cut down the production of the machine.

When drawing the string work from the machine by the interconnection of wrap threads

only, a very delicate but nevertheless positive take-up action must be provided. The take-up mechanism must likewise be so constructed as to have no detrimental effect upon the wrap threads themselves since there is a time at which the said take-up must be drawing the fabric by means of the wrap threads only.

If an elastic top is being knitted, especially a long elastic top, there is a tendency for that top to bunch up so that as the take-up draws the fabric, there will be a time when the fabric engaging rollers draw through the loopers rounds of one knitted stocking, then engage and pull by means of the interconnecting wrap threads only whereupon the next encountered fabric of a following knitted article will be an elastic top and it may, as above stated, bunch up and tend to resist entry between the take-up or fabric engaging rollers. For satisfactory operation with this method of knitting the positively driven rollers must be so mounted and pressed against the fabric as to separate to a relatively great extent for the entry of the bunched-up fabric and yet must be positively and synchronously driven. These and other characteristics of the invention will be developed as the same is described by reference to one particular embodiment of the same as applied to a hosiery knitting machine and as illustrated in this case.

Now referring to the figures of the drawings and especially Figs. 1 and 2, enough of the hosiery knitting machine has been shown so as properly to associate the parts of the take-up. A frame 1 has attached at its upper edge a base 2 within which is rotatably mounted a needle cylinder 3 having needles generally indicated by numeral 4 and which are preferably of latch type. A main cam shaft 5 would carry the usual cam drums, only one of which is illustrated in this case since it is necessary to employ only one row of cams for control of the take-up action. With reference to Fig. 5, the cylinder 3 is attached to rotate with a bevel gear 6 which is mounted for proper working bearing within the base 2 and a cap or plate 7. In wrap stripe knitting machines drive for the wrap spindle is taken from a ring gear 8 which is also attached to rotate with the gear 6.

Preferably the take-up is mounted directly beneath the cylinder and attached to rotate with the cylinder, gear 6 and also gear 8, in the event the machine is a wrap stripe knitting machine of the Banner type. The take-up is more or less self-contained within or upon a frame having a lower tubular part 9 which flares out or is cast

in such a manner at the top as to present mounting lugs 10 and 11 at opposite sides and parallel sides 12 and 13 which are slotted as will herein-after be described for the purpose of supporting spindles on which the fabric engaging rollers are driven. A series of screws 14, four such screws being employed here, attach the take-up to the gear 6. These screws pass through holes in the ears or lugs 10 and 11, then upwardly through a spacing member 15, through a ring gear 8 and are threaded through the main cylinder supporting and driving gear 6. As shown in Fig. 2, the tubular part 9 is cut away just beneath the flared or rectangular upper part of the take-up frame or casing. That allows access to the parts and makes assembly and manufacture simpler.

Now referring to Figs. 3, 6 and 7, two spindles 16 and 17 are mounted at the upper part of the frame, these spindles being flattened as at 18, Fig. 3, the flattened ends sliding in the slots 19, there being one slot in each of the parallel sides 12 and 13. At one end of each spindle a collar 20 is fixed by means of a set screw 21 and by these collars, axial movement of the spindles 16 and 17 is limited. Each of the collars is rounded at the outer side so as to allow the spindles to move in their slots and to assume different angular relationship without binding. These spindles and, of course, the fluted fabric engaging rollers on the spindles may move a considerable distance to and from each other to accommodate different sizes and weights of fabric passing between them, or either spindle may move to a limited extent at one end without a similar movement at the other. In other words, they are to a great extent universally movable in a single plane. The degree to which they may separate is such that any fabric of a type knitted in hosiery machines may easily be engaged between the rollers or even puckered or bunched up fabric such as the stocking tops above mentioned may be drawn into the rollers without especial difficulty.

At the right hand side, Figs. 3, 6 and 7, springs 22 and 23 connected at a centrally located stud 24 also connect to adjustable plates 25 and 26, Fig. 1, and are under tension sufficient to pull the ends of the spindles 16 and 17 together. These plates 25 and 26 are slotted as shown and when proper tension on the springs has been set, are locked in position by tightening the screws which pass through the slots and into the flattened ends of each spindle.

At the opposite ends of these spindles as shown at Fig. 5, similar plates 27 and 28 are connected and a single spring 29 gives that necessary tension for drawing together these ends of the spindles, this adjustment of the tension on springs 22, 23 and 29 making it possible to set the amount of take-up traction exerted by the rollers so that fabric may be drawn through without any appreciable slipping yet no excess pressure be exerted such as would damage the fabric or wrap threads, or prevent easy separation of the said fabric engaging rollers for drawing in a large mass of material if necessary.

Now referring to Figs. 3 and 10, fluted fabric engaging rollers 30 and 31 are mounted for rotation on spindles 16 and 17, bearings such as 32 and 33 being employed to reduce friction of the turning elements. These bearings are preferably of oilless type and thus do not need lubrication or attention except after a long period of usage. Each of the rollers has inserted in one end which

34 which has ratchet teeth 35 cut at its projecting end. This bushing is a press fit in the roller and is also held by solder so that when the said bushing is ratcheted by mechanism hereinafter to be described, the attached roller will likewise be rotated. The ratchet wheel 36 is similar to the other wheel having teeth 35 and drives roller 31 in similar manner. The teeth on the wheels are inclined in opposite directions so that the wheels will likewise be driven in opposite directions for advancing the fabric between them.

At the driving end of the rollers there are employed combined collars and pawl holders 37 and 38. These collars are in some respects similar to collars 20 in the opposite ends of the spindles and are set screwed to the ends of spindles 16 and 17 as shown with respect to spindle 17, Fig. 10. On the extensions or projections from these collars are carried pawls 39 and 40 pressed by means of springs 41 and 42 to engage teeth on the ratchet wheel. These pawls prevent rotation of the wheels and of the rollers 30 and 31 in a reverse direction. Details of one of these collars, the pawl and spring, as well as the pivot for the pawl, are shown in Fig. 8.

Now referring to Figs. 3, 4, 5 and 9, the rollers are ratcheted by means of two pawls 43 and 44, pawl 43 being pressed by spring 45 and pawl 44 being pressed by spring 46 into engagement with teeth of their respective ratchet wheels. In Fig. 9 the upper ends of these pawls are shown and it can be seen that each has two claws or teeth by means of which the teeth on the ratchet wheels are engaged. These pawls pivot at 47 to a reciprocable slide 48 which is vertically maintained in a groove cut in a slide holder 49 permanently attached to the circular part of the casing. The casing is cut out at that particular side for the purpose. Two plates 50 and 51 retain the slide 48 in the groove of element 49 yet provide a sliding fit. The slide 48 is drilled out as shown at Fig. 3 and a spring 52 connects adjacent the upper end of said slide and also to a pin 53 adjacent the lower end of the casing normally tending to pull the slide and pawls downwardly. This spring has sufficient tension to ratchet the fabric engaging rollers against the pull of the fabric and thereby to draw it from the needles. As can be seen, pawl 43 ratchets the fluted roller 30 while pawl 44 affects roller 31. Each roller will be moved one tooth or two teeth depending upon the position of a cam which will periodically move the slide 48 upwardly against the tension of spring 52 whereby the spring will then draw the parts downwardly eventually taking up the fabric as it is knitted. The said spring 52 is to be of such tension or adjusted for a certain amount of tension just sufficient to take up the fabric and if the fabric does not come from the needles fast enough, the pawls 43 and 44 may not engage a tooth each time the slide is raised.

As the fluted rollers are moved apart, springs 45 and 46 will always maintain the pawls in engagement with their respective ratchet wheel teeth. This construction is arranged to rotate the rollers 30 and 31 no matter what their position may be. Contrary to the arrangement commonly employed in take-up mechanisms of this type, the roller is not depended upon for driving the other and even though operated so that their flutes do not engage at all as illustrated in Fig. 7, the ratcheting of the rollers and take-up action on the fabric will still be maintained.

The slide 48 carries a cam engaging roll 54 which rotates on bushings carried by screw 55.

This roller is adapted to be engaged by a cam 56, Figs. 1 and 2, said cam 56 being movable vertically to vary the movement imparted to the pawls and also for the purpose of rendering the take-up active or inactive at desired times. The pawls are guided within a slot in a guide plate 51, Figs. 3 and 5.

Now referring to Figs. 1 and 2, the widening pick bracket has been somewhat modified so as to extend downwardly as at 58, and in addition to carrying the widening pick lever 59, provides a grooved guide element 60 within which a cam carrying slide 61 is vertically movable. Plates 62 and 63 enclose the groove and confine element 61 so that the same is movable in a vertical direction only.

The lever 64 is pivoted to a bracket or support 65 at the pivot point 66 and engages a pin 67 at the lower end of the cam carrying slide 61. A spring 68 normally tends to move the lever 64 in such a direction that the cam 56 will move to a lowermost position in which it would not engage roll 54 and would have no effect at all on the ratcheting mechanism for turning the fabric engaging rollers.

A second lever 69 pivoted at 70 to a bracket extending from the frame has a cam engaging toe 71 which is, at different times in the knitting of a stocking, controlled by cams 72, 73 and 74 on a cam drum 75 on the main cam shaft 5, Figs. 1 and 2. At the outer end this lever 69 connects by means of a link 76 to the outer end of the first mentioned lever 64. Adjustment is provided by a locking nut 77 so that proper positioning of cam 56 may be controlled. When the toe of the lever 69 is raised by any one of the cams on the drum, the outer end of lever 64 is pulled down thereby raising cam 56 so that it will engage roll 54 and render the take-up active. At other times, the said cam will be maintained in lowermost position as the toe of the lever rests upon the drum 75 and the take-up will not operate. It is, of course, desirable to discontinue the take-up action during reciprocatory knitting as in knitting the heel and toe. It is also of advantage to discontinue take-up action when knitting an elastic top, that is, especially when the fabric is being drawn down by the wrap threads only. At that time there is a tendency to pull wrap threads from the source of supply. Normally the take-up rolls tend to draw the fabric much faster than it is being knitted and thus considerable wrap yarn may be pulled from the supply, that being something which should be avoided.

The cam 72 raises the cam 56 to a position for working the take-up during knitting in the leg. When knitting the heel the take-up is inactive whereupon at the foot, cam 73 again effects cam 56 so as to start the take-up. During knitting the toe take-up action is discontinued but again at the loopers rounds cam 74 acts to accomplish the same purpose as do corresponding cams 72 and 73. Between the end of cam 74 and the start of cam 72, the elastic top, or at least part of the elastic top, is being knitted. Of course, this operation may be varied if desired and the take-up might operate during knitting the elastic top especially if the string work were to be connected by a breaking thread or connecting means other than the wrap threads.

At the top of the take-up casing a sheet metal guiding element 78 is attached about a spacing ring 79 and has an opening therein just sufficient to allow the fabric to pass down between the rollers 30 and 31, see Fig. 6. This opening is also

of a type to prevent the fabric running out upon or even toward the ends of the rollers, in other words, keeps the fabric in toward the center so that it is always engaged by the fluted rollers and can not become caught in the actuating parts.

After leaving the rollers and passing down through the tubular part of the take-up frame, the fabric is guided by a pair of sheet metal plates 80 and 81. These plates are riveted to bars 82 and 83 which are in turn connected by bolts to the tubular framework or to the slide holder 49. These sheet metal plates 80 and 81 are flared outwardly at the top so as to catch any fabric or wrap threads coming through the rollers and confine or guide it toward the center.

The invention has been described by reference to one particular embodiment of the same as applied to a hosiery knitting machine, but it is to be understood that it is not limited to that field only but may be used in other knitting machines and for taking up fabric of any type. One particular method of operation has been described in which a spring is tensioned as the roller 54 moves upwardly under influence of cam 56, but it is to be understood that the cam may be so positioned as to act positively whereupon a definite ratcheting movement of the take-up rollers will be effected each time the cam is engaged.

One type of pawl and ratchet mechanism has been disclosed, but it is to be understood that variations are permissible and that the said elements may take any one of many different specific forms all as contemplated in the original concept. The take-up may be positioned at a lower elevation in the machine and may be provided with a so-called can or other receptacle in which the fabric may be gathered as it is drawn through the take-up. The invention is defined in the appended claims.

I claim:

1. A fabric take-up for knitting machines having fabric engaging rollers each of which is independently and synchronously driven, spindles upon which said rollers rotate and on which they may move in parallel or angular relationship to and from each other together or independently throughout an extent sufficient to separate said rollers entirely.

2. A fabric take-up for knitting machines including in combination a casing, a pair of fabric engaging rollers, means for driving each of the rollers independently and synchronously, spindles on which said rollers are to be driven each of which is movable in a plane so that the said rollers may be separated wholly out of engagement or may be moved independently throughout an appreciable angular extent without disturbing the synchronous driving of each roller.

3. A fabric take-up for knitting machines including in combination a casing, a pair of fabric engaging rollers, spindles, one for each roller and upon which it may rotate, slots in the casing within which said spindles are guided and along which their ends may slide so that the said rollers are movable independently or together through an appreciable extent, driving means for said rollers including a pawl and ratchet wheel for each of the rollers, the construction being such that the rollers may be moved wholly out of engagement with each other without affecting the synchronous driving of each roller.

4. A fabric take-up having in combination a casing, a pair of fabric engaging rollers, spindles on which said rollers rotate, slots in the casing in which the ends of said spindles may move uni-

versally in a single plane throughout such an extent that the fabric rollers may be separated wholly out of engagement with each other, a pawl and a ratchet wheel operable for driving each roller and a common slider to which said pawls are pivoted and by means of which they are to be given a ratcheting movement, spring means for moving said slider in one direction and cam means for positively moving it in the opposite direction.

5. A fabric take-up for knitting machines having in combination a casing, fabric engaging rollers, spindles on which said rollers may rotate, slots in the casing and within which the ends of the spindles are movable universally throughout a limited extent in a single plane, spring means for drawing the ends of said spindles together, a ratchet wheel on each roller and by means of which said roller may be driven, a slider movable in the casing and a pair of oppositely directed pawls pivoted to said slider, one engageable with each of the said ratchet wheels, spring means for maintaining engagement between each pawl and its ratchet wheel, the construction being such that the rollers and the spindles on which they rotate may be moved independently or together throughout a limited extent at least sufficient so that the rollers may be entirely separated from engagement with each other without affecting the synchronous driving thereof.

6. A fabric take-up for knitting machines having in combination a casing, fabric engaging rollers, spindles on which said rollers may rotate, slots in the casing and within which the ends of the spindles are held against rotation but are free to slide to and from each other throughout a limited extent, spring means for drawing the ends of said spindles together, a ratchet wheel at one end of each roller and by means of which said roller may be driven, means movable and carrying a pair of oppositely directed pawls, one engageable with each of the said ratchet wheels, means for maintaining each of said pawls in engagement with its respective ratchet wheel and providing for that engagement in any of the positions to which said roller and ratchet wheel may be moved as the said spindles slide in their slots.

7. A fabric take-up for knitting machines having fluted fabric engaging rollers each of which is synchronously driven, spindles on which said rollers rotate, means for maintaining said spindles in alignment in a single plane, but allowing limited movement of either end of said spindles to and from the other so that said rollers may separate and assume different positions either parallel or angularly with respect to each other through an extent such that the flutes of said rollers may be entirely disengaged.

8. A fabric take-up for knitting machines having in combination a casing, fabric engaging rollers, spindles on which said rollers may rotate,

slots in the casing and within which the ends of spindles are movable universally throughout a limited extent in a single plane, spring means for drawing the ends of said spindles together, 5 a ratchet wheel on each roller and by means of which said roller may be driven, means movable on said casing and having pivoted thereto pawls one of which is engageable with each of said ratchet wheels, spring means for maintaining 10 that engagement with each of the said ratchet wheels irrespective of the position of one or both of the said rollers, and a stop pawl for each of the ratchet wheels to prevent reverse movement of either roller.

15 9. A fabric take-up for knitting machines having in combination a casing, fabric engaging rollers, spindles on which said rollers may rotate and guiding means for the said spindles providing movement of either or both rollers to and from the other either maintaining parallel relationship of the rollers or allowing them to assume angular relationship throughout a predetermined and limited extent at least such that the rollers may become separated to allow a substantial 25 space between them, driving means including a pawl and ratchet for each roller and means for simultaneously moving each of the pawls to engage a tooth on its respective ratchet wheel and for maintaining said pawls in engagement with their ratchet wheels no matter what the position of said rollers may become, whereby said rollers may move to and from each other and become entirely separated without disturbing the synchronous driving thereof.

30 10. A fabric take-up for knitting machines including in combination a casing, a pair of fluted fabric engaging rollers, means for driving each of the rollers independently and synchronously, spindles on which said rollers are to be driven 40 each of which is movable in a plane so that the said rollers may be separated by moving either or both of them parallelly or in such a manner that their axes are angularly disposed, and throughout such an extent that the flutes of the 45 said rollers become entirely disengaged.

11. A fabric take-up for knitting machines having fluted fabric engaging rollers each of which is synchronously driven, spindles on which said rollers rotate, means for maintaining said spindles and rollers in alignment in a single plane, but allowing movement of each end of said spindle to and from the other so that said rollers may separate and assume different positions either in parallel disposition or with their axes 50 angularly disposed, the construction being such that when said rollers are separated so that their flutes become entirely disengaged, the driving means for each roller will still be effective to maintain synchronous rotation thereof.
